MACHINE FOR APPLYING FLIES TO PAPER BOXES.

1,269,259.

Specification of Letters Patent. Patented June 11, 1918.

Application filed October 17, 1916. Serial No. 126,097.

To all whom it may concern:

Be it known that I, WALTER C. CARLSON, a citizen of the United States, residing at Milwaukee, in the county of Milwaukee and 5 State of Wisconsin, have invented certain new and useful Improvements in Machines for Applying Flies to Paper Boxes, of which the following is a specification.

This invention relates to a machine for 10 applying lace paper leaves or flies to paper boxes and is in the nature of an improvement upon mechanisms of the class typified by the patent to Philip S. Smith, No. 825,009, dated July 3, 1906.

15 In the present instance it is my purpose to provide a machine wherein the flies or lace leaves are removed one at a time from a stack or package of the same and are automatically and adhesively applied in proper 20 position to the selected interior walls of the boxes.

A further object of the invention is the provision of a machine of this character wherein the flies or leaves may be rapidly, 25 accurately and economically applied to the boxes with a minimum expenditure of time and labor, and consequently with economy from the standpoint of cost.

Furthermore, I propose to provide a machine of this class wherein the constituent parts are so correlated and arranged that a powerful, durable, simple and compact mechanism is provided which will occupy but relatively little floor space in the factory when compared with similar machines 5 with which I am acquainted; the construction of the present mechanism affording ready accessibility for the removal, repair and replacement of parts, should the necessity arise.

Furthermore, I provide a machine wherein the various functions are performed in such efficient manner and the movements of the machine take place in such sequence 5 that the liability of tearing the lace leaves or flies, or injuring the box during the application of the former is entirely avoided.

With the above recited objects and others of a similar nature in view, my invention 10 consists in the construction, combination and arrangement of parts set forth in and falling within the scope of the appended claims.

In the accompanying drawings:

Figure 1 is a view in side elevation of a machine embodying my invention.

Fig. 2 is a front view of the machine, certain parts being broken away to more clearly illustrate the construction and arrangement of certain of the mechanical elements.

Fig. 3 is a top plan view.

Fig. 4 is a transverse vertical sectional view taken approximately centrally through the machine.

Fig. 5 is a detail view partly in section and partly in elevation and showing a fly or leaf ready to be moved into position on the anvil.

Fig. 6 is a similar view showing the fly or leaf positioned on the anvil ready for application to an interior wall of a box.

Fig. 7 is a like view showing the presser mechanism operating on the box to cause the fly or leaf to adhere thereto.

Fig. 8 is a perspective view of a box illustrating the fly or lace paper leaf applied to one wall thereof.

Before entering into a detailed description of my invention I will briefly state that in the present instance I provide a machine having a sliding carriage on which 30 is mounted a vertically reciprocating, laterally moving support upon which the flies or lace paper leaves are stacked or piled. Located adjacent to the path of movement of this support is a rocking stencil which receives paste or other adhesive from a suitable adhesive supplying device which latter is also mounted on the carriage, and then such stencil is moved into engagement with the uppermost fly or leaf 35 of the stack to apply the adhesive to the top face of the latter along one edge portion thereof, the subsequent movement of the stencil away from the fly or leaf lifting or separating the adhesively coated 40 edge portion thereof from the remainder of the stack, as shown in Fig. 5, a suitable clamping member meanwhile acting to hold down or maintain the remainder of the particular top leaf as well as the rest of 45 the stack in proper position on the support.

As the stencil is retracted from the stack of flies or leaves, the carriage and consequently the support for the flies is shifted laterally toward a preferably stationary 50 anvil, the latter being so shaped and inclined that the lifted or separated, adhesively-coated edge portion of the top fly or leaf will ride up over the adjacent face of the anvil and rest thereagainst, as shown 55

in Fig. 6. The operator now places the box over the anvil with one of the inner walls of the box in contact with the adhesively coated portion of the top or exposed face of the fly or leaf. Suitable presser mechanism now in turn is brought into operation, as shown in Fig. 7, to cause the fly or leaf to firmly adhere to the wall of the box. The box is then removed and may be turned to have a second fly or leaf applied to the opposite wall thereof from that receiving the first fly or leaf, and the operation may be repeated on subsequent boxes, as will be evident.

At this point I wish to state that the various parts of the machine are so timed in their operation as to perform the various functions above briefly stated, in their proper sequence, and furthermore, as will hereinafter appear, the machine is so constructed that the various parts may be readily thrown out of operation at desired times.

Referring now to the accompanying drawings in detail, the letter A indicates the frame of the machine in which is journaled the power shaft 1 carrying the loose drive pulley 2 over which trains the belt 3 driven from a suitable motor. The pulley 2 is intended to be connected in driving engagement with the shaft 1 through the clutch 4 keyed to slide on the shaft 1 in a well known manner. The yoke 5 of the clutch is connected at its lower end with a small rocking stud shaft 6 which passes through and finds a bearing in the adjacent portion of the frame. To the outer end of the stud shaft 6 is attached an arm 7 connected through the adjustable link 8 with the arm 9 on the outer end of the rocking stud 10, the inner end of such stud 10 terminating in a head 11 to which is pivotally connected, as at 12, the bell crank lever 13, the upper end of which carries the cam roller 14 for the purpose hereinafter described. The arm 15 of the bell crank is connected through the link 16 with the foot treadle 17. The power shaft 1 is provided with a worm pinion 18 meshing with the worm gear 19 on the counter-shaft 20 which forms the main operating shaft of the machine. The gear 19 has an eccentric cam plate 21 bolted to one face thereof adjacent to the periphery of the gear and which plate co-acts with the cam roller 14 of the bell crank 13 for the following purpose: When the operator depresses the foot treadle 17 by bearing down on the foot plate 17' thereof the bell crank is rocked to move the cam roller 14 out of the path of the cam 21 traveling with the gear 19 and the clutch 4 will remain in driving connection with the pulley 2, to cause the continuous rotation of the power shaft 1, as the clutch spring 5' normally thrusts the

clutch into driving engagement with this co-acting pulley. When the operator, however, releases the foot pressure on the treadle 17 the bell crank lever 13 will be restored to its normal position with the cam roller 14 moved into the path of the cam 21, and as the latter strikes against this roller 14 it will rock the bell crank and lever 13 outward so as to turn the stud 10, thus swinging the arm 9 outward or toward the front of the machine and through the link 8, arm 7, shaft 6 and clutch yoke 5, will disconnect the clutch 4 from the pulley 2, thereby cutting off the power from the shaft 20. Thus, so long as the operator maintains foot pressure on the treadle 17 the machine will be continuously driven while when such foot pressure is relieved the machine will be disconnected and automatically stopped, so that danger to an unskilled operator will be obviated by the fact that the machine is automatically thrown out of operation by the cam revolving with the gear 19, when the operator removes the foot pressure on the treadle.

I will now describe the construction and operation of the gum-applying-stencil-device, by means of which glue, or other adhesive, is applied along one edge portion of the fly or leaf. Mounted on the top of the frame A are supporting standards 22, each carrying at its upper end a tubular bearing 23, these bearings forming a support for the stencil operating rock shaft 24. This rock shaft 24 receives its motion through the arms 25, which are fastened to the ends of the shaft and are loosely connected as at 26 to the crank rods 27 which at their lower ends are connected through crank arms 28 to the counter-shaft 20, the connecting ends of the crank arms 28 being seated in the sliding spring tensioned bearing blocks 29 of the crank rods 27, as will be readily understood by reference to Figs. 1 and 2. As will be apparent when the shaft 20 is rotated a reciprocatory movement will be imparted to the crank rods to rock the shaft 24. Pinned to this rock shaft 24 are the arms 30, the upper ends of which terminate in inwardly extending heads 31 provided with short stud-like projections 32 adapted to be received in the open face notches 33 formed in the side bars 34 and adjacent the upper ends of the latter, the terminals of these bars 34 being connected through the rod 35. The lower end portions of the side bars 34 are curved downward as at 34' and pivotally connected as at 36 to the intermediate bowed sections 37' of the arms 37, the latter in turn being pivotally connected as at 38 to the side plates 39 of the frame A of the machine. The upper ends of these arms 37 are connected by the handle bar 40 and between the pivot points 38 and just below the handle bar 40 these arms 37 are pro-

vided with inwardly extending studs 41 to which are loosely and swingingly connected the hanger 42 carrying the glue-applying stencil 43, which may be of rubber or other suitable material, and is preferably held on the bar section 42' of the hanger by means of a clamping plate 44. It will be noted that when desired, as when in testing the glue applying mechanism prior to actual 10 commercial operation, the bar 35 may be grasped and lifted so that the side bars 34 are disconnected from the grooved heads 31 of the arms 30, and consequently from the rock shaft and the operator may grasp the 15 handle bar 40 and manually raise and lower the stencil relative to the stack of flies or leaves.

The mechanism for supplying the glue to the stencil, which is indicated as an entirety 20 by the letter P, includes a glue tank or receptacle 45 mounted on the sliding side bars 46 which form a part of the sliding carriage C, this carriage being adapted to be reciprocated back and forth on the frame A of the 25 machine and carrying the glue supplying device, as well as the support for the flies or leaves, as will be hereinafter described. In order to reciprocate or slide the carriage C I provide a cam wheel 47 mounted on and 30 turning with the shaft 20 the eccentric groove 48 in this cam, having rotating therein a roller 49 at the lower end of the lever 50, the upper end of said lever being loosely supported on the rock shaft 51. This lever 35 50 is provided with a laterally extending arm 52 flexibly connected through a link 53 with the lever 54 connected with and mounted upon the shaft 55, this shaft carrying at each end an arm 56 connected through a link 40 57 with the adjacent sliding bar 46 of the carriage. Thus, as the cam wheel 47 rotates with the shaft 20 and the lever 50 is swung or oscillated on the shaft 51, the carriage will be reciprocated back and forth through 45 the lever and link connections just described.

As before stated this sliding carriage supports the glue receptacle 45, and socketed in the walls of such receptacle as at 58 are the stud shafts of the glue applying roller 59, which are adapted to be revolved in the bath of glue in the receptacle 45. Bearing against this glue applying roller 59 is a ductor roller 60 intended to cause the even and uniform application of the glue to the 55 roller 59, as will be readily understood. The ends of this ductor roller 60 are mounted in the bearings 61 at the upper ends of the arms 62, these arms being pivotally connected at their lower ends as at 63 to the adjacent sides of the tank or receptacle 45. Adjusting screws 64 are employed to bear 60 against the arms 62 and thus hold the roller 60 adjustably in engagement with the roller 59. In order to impart a partial revolution 65 to the glue applying roller 59 with each for-

ward movement of the sliding carriage, and thereby insure that the roller will at all times be freshly supplied with the glue, I provide a gear 65 which is loose upon one of the stud shafts 58 of the roller 59 and this loose gear 65 has extending from the inner face thereof a pawl 66 which is held in engagement with a ratchet 67 on the said shaft 58 by means of a small spring 68. The loose gear 65 meshes with a rack 69 bolted to the top of the frame A of the machine, and it will thus be seen that as the carriage moves forward this gear wheel 65 meshing with the rack 69 is correspondingly rotated and will through the pawl and ratchet connection 70 partially rotate the glue applying roller 59, while upon the return or backward movement of the carriage the pawl will ride idly over its ratchet and no rotational movement will be imparted to the roller 59. Furthermore, on the shaft 58 of this roller 59 and adjacent the loose gear 65 is a gear wheel 75, which is fast with the shaft 58 and meshes with a pinion 71 fast on the adjacent end of the ductor roller 60, so that when the glue-applying roller 59 is turned a rotational movement will likewise be imparted to the roller 60. If desired, a thumb wheel 72 may be employed for manually turning the roller 59 and the roller 60 geared therewith, as 80 90 when the machine is about to be started and it is the purpose to freshly coat the roller 59 with the glue. It is to be understood, as will be seen by reference to Figs. 1 and 4, that as the carriage with the glue tank 100 moves forward the roller 59 receives a fresh supply of glue through the partial rotation just described and such roller is brought or moved beneath the descending stencil which comes into contact with the surface of the 105 roller and receives a coating of the glue, while when the stencil is rocked forward and downward to apply the glue to the top leaf or fly of a stack of such leaves or flies, shown at F, the glue tank and the carriage 110 are moving rearward while when the glue stencil leaves the stack or pile of the leaves or flies after having applied the glue to the topmost one thereof the carriage starts its forward movement, of course carrying with 115 it the glue tank and the support for the stack F, as I will now proceed to describe with special reference to such support.

Preferably formed integral with and depending from the forward ends of the sliding bars 46 of the carriage and forming part of such carriage, are the vertical bars 73 connected at their lower ends by the slotted cross bar 74. Adjacent their upper ends these vertical bars 73 are connected by a 120 cross bar 75 having extending rearwardly therefrom a slotted platform or grid 76, which taken in conjunction with the bar 75 forms a support or rest for the stack of flies or leaves F. The cross bar 75 is 125 130

rabbeted at its front face as at 77 and has bolted to the front face a plate 78, the rabbet and plate forming a longitudinal slot into which may be dropped angle blocks 79, the 5 top horizontal faces of these blocks forming a continuation of the support or table for the flies or leaves, and it is further to be understood that a sufficient number of these angle blocks may be placed in position to 10 accommodate leaves or flies of the desired length. Referring to Fig. 4, it will be seen that formed integral with the bar 75 of the leaf support is a stud 80 from which depends a shank-rod 81, this rod 81 extending 15 through a bore 82 in the bar 74 and below the latter the rod passes loosely through a sleeve 83. An expansion spring 84 normally tends to push forward on the stud 80 and consequently lift the leaf support. Pinned 20 to the sleeve 83 is a yoke 85 having a projecting face 86 adapted to fit in the cut-away section 87 of the sleeve so that this projecting face of the yoke may frictionally engage with the rod 81 to pull the latter downward 25 and toward the support for the leaves, as hereinafter described, a small amount of lost motion existing between the yoke and the sleeve by reason of the fact that such yoke is pivoted as at 88 to a link 89, the 30 lower end of said link being pivotally connected as at 90 to a lever 91 mounted to rock on the shaft 92. This lever 91 is provided with a handle 93 by means of which it may be manually depressed by hand, or 35 if desired, such lever may be depressed by means of the spring tension link rod 94 pivoted as at 95 to the foot treadle 96. However, when the machine is in operation, the lever 91 is depressed or rocked downward 40 to cause the projecting face 86 of the yoke 85 to engage with the rod 81 and pull downward on the latter, thus lowering the support carrying the leaves F, because the cam 97 on the shaft 20 in its revolution will contact with the roller 98 on the lever 91 and depress such lever. After the cam has 45 passed the lever will be restored to its normal elevated position by means of the spring 94' surrounding the link rod 94, this motion being assisted to some extent by the spring 84, surrounding the shank rod 81, and consequently the leaf support or table will be again elevated. For the purpose of maintaining the flies or leaves F properly 50 and evenly stacked on their support or table I provide a series of front fingers 99 shown in Figs. 2 and 4, and which are adjustably fastened at their lower ends by thumb-bolts 100 passing through the slots of the bars 74, 55 the upper free ends of these front fingers having turned-in or hooked ends 101, which overlie the adjacent front edge of the stack. Likewise, a guide member 102 having a series of guide fingers is provided, the 60 slotted horizontal foot block 103 of said mem-

ber sliding on the slotted horizontal extension 74' of the bar 74, a suitable adjusting screw 104 passing through the slots of the foot block and extension and is provided for properly adjusting this guide member 102 70 relative to the rear face of the stack F, the upper portions of the fingers of the guide members 102 of course projecting up through the slots in the grid 76, as will be understood by reference to Figs. 5 to 7 inclusive. A 75 removable clamping plate 105 is placed to overlie the stack of leaves or flies as shown in Fig. 3, the upper terminals of the fingers of the guide member 102 projecting into the slots of the plate 105. The front longitudinal edge 106 of this plate is beveled to form a thin edge which constitutes a guide in the application of the glue to the top face of a fly or leaf, this edge 106 limiting the width of the strip of glue applied to the 80 leaf.

As the stencil rocks forward and downward and contacts with the uppermost leaf or fly, as shown in Fig. 4, it applies a strip of the glue to the front edge portion of the 9 top face of the uppermost sheet, the sliding carriage being in retracted position. As the stencil starts on its retractive movement, after such operation, as shown in Fig. 5, it partially lifts or separates the front portion 9 of the top leaf from the remainder of the stack, the clamping plate 105 of course holding the remainder of this top leaf in contact with the rest of the stack. At this time the forward lateral movement of the 1 stack support, occurring with the forward movement of the sliding carriage, as before described, now brings this separated longitudinal edge portion of the top leaf against a stationary anvil X as shown in Fig. 6. 1

This anvil X and its related parts, are preferably constructed as follows: The numeral 107 indicates a U-shaped holder bar mounted to rock outward and downward on end pivots 108, a screw rod 109 passing longitudinally through the U-shaped holder, the ends of this screw rod projecting beyond the sides of the frame, and which frame sides are formed with open-mouth slots 110, to permit the outward and inward movement of the rod with the U-shaped holder when desired, suitable pivoted latch bars 111 having slots 112 for receiving the ends of the screw rod to lock the latter in position. When it is desired to swing the U-shaped holder and rod outward, to expose the parts of the machine immediately in the rear thereof, it is only necessary to lift the latching bars 111 and grasp the milled heads 113 of the rod, when the holder may be swung as desired. Threaded on the rod and adjustable by means of the latter, are blocks 114 for clamping the anvil sections 115 together to form the complete anvil. The complete anvil X is formed of a series

of these anvil sections 115, and each section comprises a slotted shank 116 the open ended slot 117 of which is adapted to receive the screw rod 109 when the anvil is dropped 5 into the holder, a flange 118 on the front face of the anvil resting on the shoulder 119 of the front wall of the U-shaped anvil holder, while a rear shoulder 120 on the anvil rests upon the top edge of the rear 0 wall of the holder, as clearly shown in Figs. 5 to 7 inclusive. The head of the anvil is formed with a relatively wide inclined wall 121 terminating at its upper end in a V-shaped flange 122, the wall 123 of which extends at right angles to the wall 121, and it is against this wall 123 that the separated or free edge of the fly or leaf is adapted to rest. A suitable number of spare anvil sections may be supported on a bracket *b* at the front of the machine, and when necessary the complete anvil may be made up of the desired number of sections 115, the width of the complete anvil of course depending entirely upon the width of the lace to be applied to the box, the anvil preferably being made wide enough to accommodate the lace throughout its entire length. After the lace has had the adhesive applied thereto and is moved against the anvil, as shown in Fig. 6, the operator may take a box *B* and inverting the same, place one of the side walls of such box in contact with the adhesively coated edge of the fly or leaf, as shown in Fig. 7, the glue-applying stencil of course having at this time started on its rearward or retracted movement.

The presser device for firmly pressing the wall of the box against the adhesively coated edge of the fly or leaf, with the anvil as an opposing support, to properly fasten the fly or leaf within the support is now brought into operation.

The presser device embodies, in the form shown herein, a stepped bar 124 in the forward end of which is seated an angular rubber strip 125 which of course is adapted to contact with the outer face of the side of the box *B*, this rubber strip being held in place by the plate 126. The ends of the bar 124 terminate at, and are preferably connected integral with the depending rock arms 127, which are mounted to rock on studs 128 at opposite sides of the frame of the machine, the lower ends of these rocker arms being pivotally connected at 129 to links 130, which links are in turn loosely connected as at 131 to arms 132 carried at the ends of the rock shaft 51. This rock shaft 51 is actuated to swing the presser device by means of a lever arm 133 fastened to the shaft 51 by means of a set screw 134. The outer end of the lever arm is connected as at 134 to the shank end of a link bar 135, the lower end of this link bar being bifurcated to provide the spaced arms 136. These arms 136 carry

the sleeves 137 through which loosely pass the shanks 138 of the spaced members 139, the latter being pivotally connected at their lower ends, as at 140, to the forked rocker arm 141 mounted to rock on the shaft 92, the free or forked ends of this rocker arm 141 carrying the cam roller 142 against which is adapted to bear the cam 143 fast on the shaft 20, this cam in its travel passing through the forked sections of the rocker arm 141 and the link bar 135. The coil springs 138' which surround the shanks 138 above the sleeves 137, are confined by suitable nuts 137' and normally tend to pull up on these shanks and thus hold the cam wheel 142 against this actuating cam 143. Of course as the toe 143' of the cam bears against the cam roller 142, it depresses the rock lever 141, pulling down on the link bar 135, thus pulling the lever arm 133 downward, rocking the shaft 51 to draw the arms 132 toward the rear of the machine, thus pulling on the link 130 and rocking the presser bar with its rubber strip downward into contact with the box to press the latter firmly against the upturned end of the leaf or fly lying on the end and thus causing such leaf or fly to adhere to the interior wall of the box. When, however, the toe 143 of the cam has passed its cam roller 142 and such roller is bearing against the heel portion of the cam the reverse movement takes place, that is to say, the rocker arm 141 carrying the cam roller is drawn upward, by the springs 138', keeping the roller in contact with the cam, assisted by the action of the large contractile spring 144, one end of which is connected to the bracket 145 carried by the link bar 135, the other end of which is connected to the ear of the collar 146 on the shaft 55. Of course this movement will draw the presser to its retracted position, or away from the box, this occurring at the time the glue applying stencil is again moving into glue applying position. In other words, it will be understood by reference to Figs. 5, 6 and 7, the leaf support with the stack of leaves receives the glue from the stencil while the presser is retracted, such support at this time being in elevated position, and at the limit of its lateral movement away from the anvil *X* because the carriage at the time of the application of the glue is in its retracted position. However, as the stencil moves away from the leaf support, after having applied the glue to the top leaf, the presser is simultaneously moved forward to accomplish its pressing operation, the support carrying the stack of leaves being simultaneously moved forward toward the anvil to cause the elevated end of the uppermost leaf to lie on the anvil, this being due to the forward movement of the carriage at this time. When, however, the presser is performing this pressing op-

100

130

eration, the table supporting the leaves is lowered and moved into its position away from the anvil ready to be elevated the instant the pressing operation is accomplished. It will, therefore, be understood that the machine operates very rapidly and in sequence. The distance the carriage travels back and forth is very slight, and consequently but a small lateral movement is imparted to the support for the stack of leaves, this enabling the sequential operation of the glue-applying stencil, the presser and the elevating and lateral shifting of the leaf support to be accomplished as described.

5 While I have herein shown and described the preferred embodiment of my invention, I wish it to be understood that I do not confine myself to all the precise details of construction herein set forth by way of illustration as modification and variation may be made without departing from the spirit of the invention or exceeding the scope of the appended claims.

What I claim is:

25 1. A machine of the class described embodying in its construction a box-supporting anvil and a support for a stack of flies independent of the anvil and movable toward and from the latter to bring a portion 30 of one of the flies of the stack into position to overlie an adjacent wall of the anvil.

2. A machine of the character described embodying in its construction a box-supporting anvil, a support for a stack of flies, and means for moving the support laterally toward the anvil to bring an edge 35 portion of the uppermost fly of the stack into position to overlie the anvil.

3. In a machine of the class described, an 40 anvil, a support for a stack of flies, means for applying an adhesive to a fly on the support, means for moving the support bodily toward the anvil to bring the fly into a position to overlie one wall of the anvil, and a presser device movable toward and from the anvil and adapted to press against a wall 45 of a box on the anvil to cause the fly to adhere to the box.

4. In a machine of the class described, an 50 anvil, a vertically-reciprocating laterally-movable support for a stack of flies, means for applying an adhesive to the uppermost fly of the stack on the support and means for imparting the lateral movement to the support to cause the adhesive leaf to overlie the anvil.

5. In a machine of the class described, the combination with a box-supporting anvil, of a laterally moving support for a stack 55 of flies, means for applying an adhesive to the uppermost fly of the stack, means for shifting the support to cause said uppermost fly to overlie a wall of the anvil, and a presser device adapted to press said over-

lying fly against a wall of a box on the anvil.

6. In a machine of the class described, a box-supporting anvil, a support for a stack of leaves located adjacent the anvil, a rocking adhesive-applying devise adapted to apply 70 an adhesive to a fly carried by the support, means for moving the support relative to the anvil to cause said adhesive fly to overlie a portion of said anvil, and a movable presser device adapted to contact with 75 the box on the anvil to cause said fly to adhere to a wall of the box.

7. In a machine of the class described, the combination with a box-supporting anvil, of a support for a stack of flies located adjacent the anvil and a rocking adhesive-applying device adapted to be rocked into engagement with the uppermost fly of the stack to apply an adhesive along one edge portion of said fly, said adhesive in its movement away from the fly partially separating the fly from the remainder of the stack, and means for bodily moving said fly support relative to the anvil to cause the separated portion of the fly to overlie a wall of the 85 anvil.

8. In a machine of the class described, the combination with a box-supporting anvil, of a support for a stack of flies movable toward and from the anvil, a rocking adhesive applying device adapted to apply an adhesive to the uppermost fly of the stack on the support, means for moving the support toward the anvil to bring the adhesively coated portion of the uppermost fly into 100 position to overlie a wall of the anvil, and a presser device movable toward and from the anvil and adapted to contact with the box on the anvil to cause said fly to adhere to the wall of the box.

9. In a machine of the class described, the combination with a box-supporting anvil, of a reciprocating carriage, a support for a stack of flies mounted on the carriage and movable toward and from the anvil with 110 a reciprocation of the carriage, means for imparting a vertically reciprocating movement to the support, a device for applying an adhesive to a fly carried by the support, and a presser device adapted to operate to 115 cause the adhesively coated fly to adhere to a box supported on the anvil.

10. In a machine of the class described, the combination with a box-supporting anvil, of a traveling carriage, a support for 120 a stack of flies movable with the carriage toward and from the anvil, a device for applying an adhesive to the flies on the support and adhesive supplying means mounted on the carriage and adapted to supply the 125 adhesive to the adhesive-applying device.

11. In a machine of the class described, the combination with a box-supporting an-

vil, of a traveling carriage, a support for the flies carried by the carriage and movable therewith toward and from the anvil, a rocking adhesive-applying device movable toward and from the fly support and adapted to apply an adhesive to one edge portion of the uppermost fly of the stack, and means for supplying the adhesive to the adhesive-supplying device.

10 12. In a machine of the class described, the combination with a box-supporting anvil, of a sliding carriage movable toward and from the anvil, a fly-support movable with the carriage, adhesive-supplying means mounted on the carriage, a rocking-adhesive-applying member adapted to receive a supply of the adhesive from the supplying means and to be rocked into contact with a fly on the support to apply the adhesive thereto, and a presser device adapted to press the adhesive fly against a wall of the box carried by the anvil when such support has been moved by the sliding carriage to bring a portion of the fly to a position to 25 overlie the anvil.

13. In a machine of the class described, a box-supporting anvil, a support for a stack of flies, a rocking glue-applying stencil for applying glue to the uppermost fly of the 10 stack and means for moving the support to bring said uppermost fly into a position to overlie one wall of the anvil.

14. In a machine of the class described, a stationary box-supporting anvil, a support for a stack of flies movable toward and from the stationary anvil, a rocking glue-applying stencil for applying glue to the flies on the support and a rocking presser device.

15. In a machine of the class described, the combination with a box-supporting anvil, of a sliding carriage, a glue tank mounted on the carriage, a glue-supplying member working in the tank, a support for a stack of the flies carried by the carriage and 5 movable toward and from the anvil with the carriage, a rocking glue-applying stencil adapted to be supplied with glue from the roller and adapted to apply the glue to the flies on the stack, and a presser device movable toward and from the anvil to press the flies against the boxes to cause the flies to adhere to the walls of the boxes.

16. In a machine of the class described, the combination with a box-supporting anvil, of a yielding support for a stack of flies located adjacent the anvil, means for bodily moving the support to and from the anvil, and a rocking glue applying stencil for applying glue to one edge portion of the uppermost fly of the stack, said stencil in its movement away from the stack partially

lifting the glued fly, said fly being brought into position to overlie a wall of the anvil on the subsequent movement of the support toward the anvil, and a presser device 65 movable toward and from the anvil and into contact with the box on the anvil to cause the glued fly to adhere to a wall of the box.

17. A machine of the class described embodying in its construction a holder member, 70 an anvil supporting member extending therethrough, an anvil section including a shank projecting into the holder, said shank terminating beyond the holder in a box-supporting section, and means for holding 75 the anvil against lateral movement in the holder.

18. A machine of the class described embodying in its construction a support for a stack of flies, such support comprising a 80 yielding table-like member upon which the flies rest, clamping guides at opposite side edges of the stack for holding the stack of flies in position on the table, a box-supporting anvil and means for shifting the fly support relative to the anvil.

19. In a machine of the class described, a box-supporting anvil, a traveling carriage, a support for a stack of flies carried by the carriage and movable therewith toward 90 and from the anvil, a rocking adhesive-applying device including a glue stencil adapted to apply glue to the flies on the support, and an adhesive-supplying device comprising a glue tank mounted on and movable with the carriage, and an intermittently rotatable member working in the glue tank and adapted to supply glue to the stencil.

20. In a machine of the class described, an anvil, a support for a stack of flies located adjacent the anvil, a clamping plate overlying the flies on the support, a glue applying stencil movable toward and from the fly support and adapted to apply glue to the edge portion of the uppermost fly on 105 the support which projects beyond the clamping plate, said stencil in its movement away from the fly being adapted to separate the glued portion of the fly from the remainder of the stack, means for moving the support to bring the glued portion of the fly into a position to overlie one wall of the anvil, and a presser device moving into operative position to cause the fly to 110 adhere to a box supported on the anvil when 115 the stencil has moved away from the fly.

In testimony whereof I affix my signature in the presence of two witnesses.

WALTER C. CARLSON.
